In France February 12, 1948

8 Claims. (Cl. 254—29.)

1

This invention relates to a movable device for driving piles and the like, which will enable, inter alia, to carry out, in the open air, piles or the like from pre-formed concrete or like sections, that are assembled together as the driving is proceeding.

The device according to the invention is of the type comprising a movable pile driving member, which is guided in the direction of driving, the said member being acted upon by operating means able to apply thereto the force required for driving, which force is transmitted to the pile or the like, the range of travel of the said member being relatively great, thus producing a continuous sinking of the pile or the like for a relatively great depth in the soil.

According to the invention, the driving member consists in a rigid structure or assembly comprising two braced beams positioned transversely of the platform of the device and extending up to the outside thereof, the said beams being spaced apart a distance greater than the thickness of the pile or the like, the said pile driving member being guided along four guides arranged in pairs on both sides of the said beams, an abutment member adapted to transmit the driving force to the pile or the like, being movable so that it may occupy any position in the space defined by the said beams, even beyond the area of the said platform in the lateral direction.

According to one convenient form of the invention, the pile driving member is provided with four nuts engaging four simultaneously operated, parallel, rotatable screw worms secured in axial position on the platform of the device and arranged by pairs laterally beyond the said platform.

According to a further convenient form of the invention, the pile driving member is guided along four parallel guides secured upon the platform and arranged by pairs laterally beyond the platform, the said member being secured to two groups of cables operated in synchronism and capable of moving the said member in either direction along the said guides.

More specifically, the device according to the invention makes it possible to sink piles or the like of considerable length, and to carry out such sinking in various points of an area extending transversely of the device, without involving displacement of the latter. The device further enables sinking action along a wall.

Further features and advantages of the invention will appear from the disclosure of two embodiments given hereinafter by way of example.

2

with reference to the accompanying diagrammatic drawings, in which:

- Fig. 1 is a side elevation, partly in section, of the central portion of the device of the invention;
- 5 Fig. 2 is a sectional view substantially on line II—II of Fig. 1;
- Fig. 3 is a sectional view of the device substantially on line III—III of Fig. 1;
- 10 Fig. 4 is a partial side elevation of a modification of the device;
- Fig. 5 is a diagrammatic plan view showing the arrangement of the main operating components. Certain details have been omitted in the drawings for the sake of clearness.
- 15 The device comprises a platform consisting essentially of two longitudinal carriers 1 and two cross pieces 2. The platform is made displaceable, conveniently by means of rollers 3 adapted to roll upon metal girders 4 resting on wooden cradle members 5 laid on the ground 6. The platform carries a tower comprising essentially two trestle girders or uprights 7 arranged transversely of the platform. The tower is stiffened by means of struts 8.
- 20 In the example shown in Figs. 1 to 3, the platform carries four identical vertical screw worms 9 arranged by pairs beyond the longitudinal members 1 in the lateral direction, the ends of the worms being rotatably supported in the platform and the upper ends of the trestle uprights 7 respectively. The worms are capable of being rotated in synchronism by any suitable operating mechanism 10, which may be actuated e. g. from a Diesel engine 11 mounted on the platform.
- 25 The worms have mounted thereon nuts made fast with each other by means of a rigid movable assembly, which, as will be seen, is adapted to be moved parallel to the worms due to the synchronous rotation of the latter, the said assembly
- 30 forming the driving member which is caused to act upon the pile or like sections, specifically upon the heads of such sections. The assembly comprises two beams 12 extending parallel to the carriers 1, each beam 12 connecting the nuts of two
- 35 respective worms 9. The beams 12 are connected to each other by girders 13 made from section iron and forming a rolling track for a carriage 14 supported by means of rollers 15 upon the lower flanges of the sections 13. The carriage 14 carries
- 40 a hydraulic jack connected by means of tubing (not shown) to a source of liquid under pressure (such as a pump operated from the engine 11), the said jack being adapted to act upon the head of the pile 17 to be sunk. Due to the fact that the
- 45 four worms are arranged laterally beyond the
- 50
- 55

carriers 1 and to the possibility of moving the jack, the sinking operation may be effected not only between the carriers, but laterally beyond the latter as well, between each pair of worms 9, more especially at the points A and B. Owing to this arrangement, the device of the invention makes it possible to drive piles and the like along an existing wall, which is a considerable advantage in many instances. The carriage 14 may consist of an I-section, the lower flange of which has attached thereto the jack 16, so that the position of the latter may also be adjusted for a certain distance laterally with respect to the rolling track formed by the sections 13. Since the reaction from the driving action is taken up by the weight of the device, the latter is provided with ballast boxes 18, which may be filled at the working yard with gravel or other material, so that the device may be given a weight a hundred of tons or so.

The device of the invention makes it possible to sink, in a single operation, pile sections of a length corresponding to the range of travel of the movable assembly 12-16, plus, if desired, the range of travel of the jack plunger, that is to say a length of six to eight metres.

By providing a speed changing gear in the transmission operating the screws 9 from the engine 11, the rate of sinking may be varied in accordance with the force required for sinking. For instance, using a 48 H. P. diesel engine, a pile section of six metres has been sunk in two minutes with a force of 15 tons, in three minutes with a force of 22.5 t., and in 5 minutes with a force of 50 t. As will be seen, the sinking is carried out at a particularly high speed. Moreover, the sinking action is effected regularly, without impact or vibration. It will be understood that one could sink pile or like sections of substantially greater length than the worms 9, but the driving action should be effected in this instance in two or more stages. Also in this instance, instead of acting upon the top of the pile, it will be necessary to act upon the periphery thereof by means of a driving member surrounding the pile and adapted to be momentarily clamped thereon.

The sinking may be advantageously effected with the aid of a hydraulic jack 16 which is intended to perform two functions:

(1.) Act as a pressure gauge that indicates continuously the force necessary for driving the pile;

(2.) Enable the sinking to be continued when the force required outranges the limit determined by the power of the engine and the mechanical strength of the transmission system, e. g. 50 t. In this instance the worms are arrested and the work is continued by the jack alone. The liquid, such as water under pressure, is supplied to the jack by a hydraulic pump which may also be operated from the engine and is thus able to give three different outputs.

Moreover, the device according to the invention is designed so that the pile sections may be conveniently brought into the required position, which was often a difficult matter with known devices.

The trestle uprights 7, which leave between them a free space in the transverse direction of the platform, are connected at their upper ends by means of a structure comprising a framework 19 supporting a ridge beam 20. To the lower flange of the latter there is attached a

girder 21 formed of assembled section iron and adapted to slide with respect to the beam 20.

The girder 21 is provided with a rolling track formed e. g. by the lower flanges of the iron sections and on which a carriage 22 is adapted to roll, the said carriage having attached to it a pulley block operated by means of a cable 23 from a winch arranged on the platform. The carriage 22 may be moved along the girder 21 by means of any known mechanism, such as by operating the chain 24 manually.

When the movable assembly 12-16 is in its lowermost position, that is to say at the lower end of the worms 9, as would be the case at the termination of a sinking action, then the whole of the space between the carriage 22 and the assembly is free in the transverse direction with respect to the platform. The pulley block of the carriage 22 may then be used to lift a pile section 17', whereupon the latter may be brought into a position perpendicularly above the sinking site by shifting the carriage. Then the pile section will be lowered until it rests on the soil or on a pile section previously sunk, such lowering being rendered possible by the fact that the two beams 13 are sufficiently spaced apart so as to allow the pile or the like to pass therebetween, and by the fact that the carriage 14 supporting the jack 16 may be moved aside to free the passage. Hence, all that need be done is to lift the assembly 12-16, to engage the jack onto the top of the new pile and to operate the worms 9.

The girder 21 should project laterally, since it is advisable that the lifting of the pile is effected outside the profile form of the device, so as to avoid interference. However, such projection would be a hindrance when driving piles or the like adjacent a wall. To eliminate this disadvantage the girder 21 may be made slid able, so that it may be shifted from one side of the device to the other, the said girder being adapted to be locked in the desired position by any suitable means such as a removable locking pin 25.

A tackle for handling the piles or the like, as just described, would facilitate and speed up the whole of the work. Such tackle may be used owing to the fact that the driving member enables piles or the like to be positioned across such member when the latter is at the lower end of its travel. Thus, owing to the combined use of the driving member and the tackle, any loss of time is avoided.

The device may be moved bodily by means of legs or crutches operated by hydraulic jacks 26 mounted on the platform. One end of each leg is pivotally connected to a frame 27 abutting upon the girders 4, the other end being pivotally connected to a bracket 28 eccentrically mounted on a plate secured to the platform and rotatable on a vertical pivot pin 29. When it is desired to vary the direction of push of the legs, all that is required is to rotate the unit 26-28 around the pivot 29.

In the modification shown in Figs. 4 and 5, the worms 9 and the operating gear 10 have been eliminated, the guiding and the operation of the driving member 12-16 being effected by separate means. Instead of being provided with nuts, the beams 12 are furnished with four guide bushings adapted to slide on vertical guides 30 which are arranged in positions similar to those occupied by the worms 9 of Figs. 1-3, such guides consisting of vertical cylindrical shafts secured onto the platform and held in position by cross members 31 pertaining to structures similar to

the trestle girders 7 of Figs. 1-3, such structures being not shown in Fig. 4.

The movable assembly 12-16 is suspended on two cables or the like 32, each cable being operated from two winch drums 33, 34 and passing on pulleys 35 carried by the cross members 31 and on pulleys 36 carried by the beams 12. Furthermore, the downward pulling force is exerted upon the driving member 12-16 by two cables 37, each of which is operated from two winch drums 38, 39 and passes around block pulleys 40, 41 and 42, 43, the pulleys 40, 42 being carried by the beams 12, and the pulleys 41, 43 by the platform.

The drums 33, 34, 38 and 39 are operated through a transmission gear (not shown) driven from the engine 11. The drums 33 and 34 on the one hand and the drums 38 and 39 on the other hand are synchronized, viz., either by pairs positioned on the same lateral side of the device, or all the four drums 33, 34 are synchronized for themselves and the four drums 38, 39 are synchronized for themselves. It will be seen that the pulleys 36 are carried by the beams 12 and are movable therewith, so that the cable 32 passing from one of these pulleys to the other does not interfere with the tackling of the piles by means of the carriage having attached thereto a pulley block 22 operated by means of the cable 23 and the independent winch 44.

To draw the driving member 12-16 downwards, it is only necessary to unlock the drums 33, 34 and the cables 32 and to operate the drums 38, 39, whereby the desired pulling force will be applied through the cables 37. To move the driving member upwardly, the drums 38, 39 and cables 37 are unlocked and the drums 33, 34 and cables 32 are operated.

Operation of the driving member through cables provides a particularly simple construction of the device and shows a further advantage in that the driving of piles or the like may be carried out at a very high speed.

It will be understood that the invention is not limited to the examples described and illustrated, as various modifications may be made therein without departing from the spirit thereof.

What I claim is:

1. A pile driver apparatus comprising, in combination, a plurality of spaced uprights forming a supporting frame; a platform located adjacent to said uprights and having guide portions thereon which extend in a horizontal direction beyond the outer limits of said uprights; means for moving said platform vertically along said uprights; a ramming device; and means for mounting said ramming device on said guide portions of said platform for movement therealong, whereby a pile may be driven at a plurality of locations with respect to said apparatus without moving said supporting frame.

2. A pile driver apparatus comprising, in combination, a base member; a plurality of spaced uprights forming a supporting frame on said base member; a platform located adjacent to said uprights and having guide portions thereon which extend in a horizontal direction beyond the outer limits of said uprights and said base member; means for moving said platform vertically along said uprights; a ramming device; and means for mounting said ramming device on said guide portions of said platform for movement therealong, whereby a pile may be driven at a plurality of locations with respect to said apparatus without moving said supporting frame.

3. A pile driver apparatus comprising, in combination, a base member; a plurality of spaced uprights forming a supporting frame on said base member; a platform located adjacent to said uprights and having guide portions thereon which extend in a horizontal direction beyond the outer limits of said uprights and said base member; means for moving said platform vertically along said uprights; a ramming device; and means for mounting said ramming device on said guide portions of said platform for movement therealong, whereby a pile may be driven at a plurality of locations with respect to said apparatus without moving said supporting frame, said means for mounting said ramming device on said guide portions comprising additional guide portions extending transversely of said first-mentioned guide portions and being operatively connected to said ramming device, so that the ramming device may be moved in two directions with respect to said supporting frame.

4. A pile driver apparatus comprising, in combination, a base member; a plurality of spaced uprights forming a supporting frame on said base member; a platform located adjacent to said uprights and having guide portions thereon which extend in a horizontal direction beyond the outer limits of said uprights and said base member; screw means for moving said platform vertically along said uprights; a ramming device; and means for mounting said ramming device on said guide portions of said platform for movement therealong, whereby a pile may be driven at a plurality of locations with respect to said apparatus without moving said supporting frame, said means for mounting said ramming device on said guide portions comprising additional guide portions extending transversely of said first-mentioned guide portions and being operatively connected to said ramming device, so that the ramming device may be moved in two directions with respect to said supporting frame.

5. A pile driver apparatus comprising, in combination, a base member; a plurality of spaced uprights forming a supporting frame on said base member; a platform located adjacent to said uprights and having guide portions thereon which extend in a horizontal direction beyond the outer limits of said uprights and said base member; pulley means for moving said platform vertically along said uprights; a ramming device; and means for mounting said ramming device on said guide portions of said platform for movement therealong, whereby a pile may be driven at a plurality of locations with respect to said apparatus without moving said supporting frame, said means for mounting said ramming device on said guide portions comprising additional guide portions extending transversely of said first-mentioned guide portions and being operatively connected to said ramming device, so that the ramming device may be moved in two directions with respect to said supporting frame.

6. A pile driver apparatus comprising, in combination, a plurality of spaced uprights forming a supporting frame; a platform having opposite outer edges and being located adjacent to said uprights, said platform having guide portions thereon which extend in a horizontal direction beyond the outer limits of said uprights and up to said outer edges of the platform, the said guide portions being located at a substantial distance from each other so that there is provided between said guide portions a space in which a pile to be driven may be accommodated;

means for moving said platform vertically along said uprights; a ramming device; and means for mounting said ramming device on said guide portions of said platform for movement therealong, whereby a pile may be driven at a plurality of locations with respect to said apparatus without moving said supporting frame.

7. A pile driver apparatus comprising, in combination, a plurality of spaced uprights forming a supporting frame; a platform having opposite outer edges and being located adjacent to said uprights, said platform having guide portions thereon which extend in a horizontal direction beyond the outer limits of said uprights and up to said outer edges of the platform, the said guide portions being located at a substantial distance from each other so that there is provided between said guide portions a space in which a pile to be driven may be accommodated; means for moving said platform vertically along said uprights; a ramming device; and means for mounting said ramming device on said guide portions of said platform for movement therealong, whereby a pile may be driven at a plurality of locations with respect to said apparatus without moving said supporting frame, said means for mounting said ramming device on said guide portions of said platform comprising additional guide portions extending transversely of said first-mentioned guide portions and being operatively connected thereto for movement therealong, said ramming device being movably mounted on said additional guide portions for movement therealong, whereby said additional guide portions and ramming device mounted thereon may be moved in one direction with respect to said first-mentioned guide portions and whereby said ramming device may be moved along said additional guide portions in a direction transverse to said one direction.

8. A platform mounted for vertical movement in a pile driving apparatus comprising, in com-

bination, a pair of substantially identical beams mounted in spaced and substantially parallel relations to each other and located at outer edge portions of the platform; a pair of cross members respectively connected at outer end portions thereof to the under sides of said beams, the said pair of cross members being located at a substantial distance from each other so that there is provided between said cross members a space in which a pile to be driven may be accommodated, the said cross members each having lower flange portions extending along the entire length thereof and being substantially parallel to said beams; roller means extending across the space between said cross members and being mounted on said lower flange portions thereof for movement therealong, whereby said roller means is movable across the entire space included between said cross members; and elongated guide means extending transversely of said cross members at the under side thereof and being adapted to slidably support the ramming device of the pile driving apparatus thereon, said guide means being connected to said roller means so as to be movable with said roller means along the entire space between said cross members, whereby, when the platform is in its lowermost position, a pile to be driven may be located anywhere in the space between said cross members and the platform then lifted to locate the ramming device over the pile thus located in said space.
